UNITED STATES PATENT OFFICE

2,115,305

SAFETY APPLIANCE FOR STOVES AND RANGES

Frederick L. Fox, Washington, D. C., assignor to Crown Stove Works, Cicero, Ill., a corporation of Illinois

Application June 17, 1936, Serial No. 85,785

3 Claims. (Cl. 126—37)

This invention relates to cooking stoves of the cabinet type in which a cover is used to conceal the burner top when the stove is not in use for cooking purposes, and has more particular reference to an improved device of the type disclosed in my U. S. Letters Patent No. 2,035,060, upon Gas cooking stoves, dated March 24, 1936, wherein means is associated with the burner top cover for preventing the burners from being turned on when the cover is in burner top concealing position, for permitting the burners to be turned on when the burner top cover is in burner revealing position, and for turning off any of the burners that might be turned on when the burner top cover is moved to burner top concealing position.

The primary object of the present invention is to generally simplify and improve the construction of the device covered by my above-mentioned patent, whereby the device may be more cheaply and easily manufactured and installed, and whereby the device will involve a minimum number of durable parts which will afford efficient operation and will not readily get out of order.

Another object of the present invention is to provide an improved device of the above kind which, in addition to being greatly simplified, may be readily adapted for use upon stoves having a different arrangement of burner control valves or elements than that disclosed in my above-mentioned patent.

With the above general objects in view, and others that will become apparent as the nature of the present invention is better understood, such invention consists in the novel form, combination and arrangement of parts hereinafter more fully described, shown in the accompanying drawing and claimed.

In the drawing, wherein like reference characters indicate corresponding parts throughout the several views:

Figure 1 is a fragmentary vertical longitudinal section through a stove equipped with a device constructed in accordance with the present invention, and with the burner top cover in open or burner revealing position.

Figure 2 is a fragmentary vertical transverse section on line 2—2 of Figure 1; and

Figure 3 is a view somewhat similar to Figure 2 taken on the plane of line 3—3 of Figure 1.

Referring in detail to the drawing, an embodiment of the present invention is shown applied to a conventional type of gas cooking stove having an upper burner box or compartment 5 and formed at 6 for removable reception of an ordinary burner top. Extending longitudinally of the stove within the forward upper portion of the burner box or compartment 5 is the usual manifold 7 which supplies gas to a plurality of burners

located in the compartment 5 below the burner top, one of said burners being indicated at 8. Each burner is controlled by a valve 9 located beneath and tapped into the manifold 7 adjacent the front wall of the burner box or compartment. 5 Each control valve 9 further has a forwardly projecting stem 10 provided with a conveniently accessible operating handle 11 which, in the stove illustrated, is located outside the burner box or compartment 5 and has a shank secured on the 10 stem of the associated valve 9 and extending through an opening in the front wall of the burner box or compartment 5. The stove illustrated further has a suitable burner top cover 12 hinged at its rear corners to the body of the stove 15 for vertical swinging movement, as at 13. Each hinge of the burner top cover may include a pivoted member having a rigid projecting arm 14 arranged to engage the top wall of the burner box or compartment as shown in Figure 3 for limiting the raising of the cover to a substantially vertical open position as shown by full lines in the latter figure.

The illustrated embodiment of the present invention comprises means for operatively connecting the burner top cover 12 with the operating stems 10 of the burner control valves or elements 9, including a Bowden wire element whose external member 15 is attached at one end to the adjacent side wall of the burner box or compartment 5 as at 16, and which extends forwardly and downwardly where it is attached adjacent its other end to the side wall of the box or compartment 5 near the front wall of the latter as at 17. The internal member or flexible wire 18 of this Bowden wire element is operatively connected at one end to the burner top cover 12 and at the other end to the stems 10 of the valves or control elements 9. As shown, the first-mentioned operative connection between the wire 18 and cover 40 12 may include a bell crank lever 19 yieldingly swung in one direction by a tension spring 20 and having the adjacent end of the wire 18 secured to the outer end of one arm of said bell crank lever 19. The bell crank lever 19 is suitably pivoted as at 21 intermediate its ends and to the adjacent side of the stove body, the other arm of said bell crank lever bearing against the under side of the projecting arm 14 on the movable member of the adjacent hinge of the burner top 50 cover 12.

The second-mentioned operative connection between the other end of wire 18 and the stems 10 of control elements or valves 9 may include a 55 slide actuating element or unit embodying a 55 rod 22 to which the adjacent end of wire 18 is attached as at 23, and which is mounted in suitable guides 24 for longitudinal sliding movement parallel with and adjacent the front wall of the box or compartment 5 and transverse to the stems 10 60

of the valves or control elements 9. It will be noted that the forward end portion of the Bowden wire element is directed laterally and inwardly toward and parallel with the rod 22 where the forward end portion of the external member 15 of said Bowden wire element is secured to the adjacent guide 24 as at 25. Thus, proper reciprocation of rod 22 may be effected by corresponding movement of wire 18. It is preferred to mount the rod 22 inside the burner box or compartment 5 on a plane slightly below the stems 10, and for this purpose the guides 24 may be secured to the inner surface of the front wall of box or compartment 5 as shown. This invention accordingly provides an operating connection between the valves or control elements 9 and the cover 12 which is located entirely within the burner box or compartment 5 and therefore completely concealed so as to not be unsightly or readily tampered with.

The actuating element or unit also includes upwardly projecting arms 26 rigid with the rod 22, and the stem 10 of each burner control valve or element 9 has a depending rigid arm 27 carrying a pin arranged in the path of an arm 28 of the rod 22, so that when the wire 18 is pulled to slide the rod 22 to the left of Figure 1, as is done when the cover 12 is closed, the arms 26 will engage and swing the arms 27 so as to turn the control valves or elements 9 to cut off the burners controlled by the latter. As the rod 22 will remain in the position to which it is thus shifted, as long as the burner top cover 12 remains closed, the arms 28 will engage the arms 27 so as to prevent such turning of the control elements or valves 10 as is necessary to turn on the burners controlled thereby. Thus, no burner may be left on when the burner top cover 12 is closed, the very operation of closing such cover bringing about the turning off of any burner which may have been lighted. Also, no burner may be turned on and/or become lighted while the cover 12 is closed, to either permit objectionable escape of gas or objectionable burning of the cover 12. It will be apparent, however, that when the cover 12 is opened, the rod 22 will be shifted to the right of Figure 1 to the position shown in the latter figure so that the arms 26 are moved away from the arms 27 and opening of the valves or control elements 9 is permitted for turning on the burners.

The above described operation will be apparent when it is considered that closing of cover 12 causes downward and rearward swinging of arm 14 so as to actuate the bell crank lever 16 and cause a pull to be exerted on the wire 18 for shifting the rod 22 to the left of Figure 1, while raising of cover 12 will permit the spring 29 to return the bell crank lever 16, wire 18 and rod 22 to the normal positions thereof as illustrated in Figures 1 and 3. It is also noted that the spring 29 is preferably of such strength as to counterbalance the cover 12 and promote its easy and noiseless movement when shifted from the raised or opened full line position of Figures 1 and 3 to the closed position as indicated by dotted lines in Figure 3.

It will be apparent that the operative connection of one end of wire 18 with the cover 12 may be considerably varied, and it will be likewise apparent that many different forms of connection may be provided between the rod 22 and the cover 12, although the preferred embodiment of the

present invention contemplates the use of both the Bowden wire element 15, 18 and the actuating unit including rod 22. Various other changes and modifications will suggest themselves to those skilled in the art without departing from the spirit and scope of the invention as claimed.

What I claim as new is:

1. In combination, a burner top, a cover for said burner top hinged at its rear edge for vertical swinging movement, an arm rigid with and projecting from said cover at an angle to the latter so as to assume a substantially vertical depending position when the cover is lowered and a substantially horizontal forwardly projecting position engaging the under side of said burner top to limit the upward swinging movement of the cover when the latter is raised, a bell crank lever pivoted directly beneath the burner top and having upwardly diverging forward and rear arms, the rear arm of said bell crank lever extending in the path of said first-named arm for actuation by the latter when the cover is lowered, and means to connect the forward arm of said bell crank lever to an element to be actuated.

2. In combination, a burner top, a cover for said burner top hinged at its rear edge for vertical swinging movement, an arm rigid with and projecting from said cover at an angle to the latter so as to assume a substantially vertical depending position when the cover is lowered and a substantially horizontal forwardly projecting position engaging the under side of said burner top to limit the upward swinging movement of the cover when the latter is raised, a bell crank lever pivoted directly beneath the burner top and having upwardly diverging forward and rear arms, the rear arm of said bell crank lever extending in the path of said first-named arm for actuation by the latter when the cover is lowered, means to connect the forward arm of said bell crank lever to an element to be actuated, and yieldable means to swing said bell crank lever in a direction to maintain engagement of the rear arm of said bell crank lever with said first-named arm and to counterbalance the cover when the latter is raised.

3. In combination, a burner top, a cover for said burner top hinged at its rear edge for vertical swinging movement, an arm rigid with and projecting from said cover at an angle to the latter so as to assume a substantially vertical depending position when the cover is lowered and a substantially horizontal forwardly projecting position engaging the under side of said burner top to limit the upward swinging movement of the cover when the latter is raised, a bell crank lever pivoted directly beneath the burner top and having upwardly diverging forward and rear arms, the rear arm of said bell crank lever extending in the path of said first-named arm for actuation by the latter when the cover is lowered, and means to connect the forward arm of said bell crank lever to an element to be actuated, said first-named arm being arranged to depend substantially in vertical alignment with the axis on which the cover is hinged and to engage at its free lower end with the rear arm of said bell crank lever to lock said bell crank lever against movement in one direction when the cover is lowered.

FREDERICK L. FOX.
